TELETYPEWRITER

Clyde J. Fitch and Kurt R. Schneider, Endicott, N. Y., assignors to International Business Machines Corporation, New York, N. Y., a corporation of New York

Application December 2, 1936, Serial No. 113,799

13 Claims. (Cl. 178—23)

This invention relates to typewriters and more particularly to typewriters for use as a receiving or recording unit in remote control systems such as for example printing telegraph systems and the like.

It is an object of the present invention to provide a simplified and positive permutation bar system associated with the character keyboard of a typewriter and adapted to operate a key bar in accordance with the permutation or combinational signals received thereby printing the selected character.

Various other objects and advantages of the invention will be obvious from the following particular description of one form of mechanism embodying the invention or from an inspection of the accompanying drawings; and the invention also constitutes certain new and useful features of construction and combination of parts hereinafter set forth and claimed:

In the drawings:

Fig. 1 is a cross sectional view of one type of power operated typewriter and the associated permutation bar unit. The cross section of the said unit is taken along lines 1—1 of Fig. 2.

Fig. 2 is a plan view of the permutation bar unit.

Fig. 3 is a detail view of the controlling clutch unit taken along lines 3—3 of Fig. 2.

Fig. 4 is a detail view of the drive gears for the bars.

Fig. 5 is an exploded view of a permutation bar clutch unit.

Figs. 6 to 6—B are detail views of the clutch unit.

Figs. 7 to 7—E are detail views of the permutation bars.

For illustrative purposes, this invention is shown as embodying a well known form of recording unit, which may be the Electromatic typewriter, and hence requires only the following brief description.

Referring to the drawings and particularly to Fig. 1, in the embodiment illustrated in the drawing, well known means are provided for actuating the type bars (not shown) by power operated devices comprising a power driven roller 10.

A cam 11 is pivoted on one arm of a bell crank lever 12 pivoted in the frame, the other arm of which is operatively connected with one arm of a bell crank lever 13 by means of link 14. The other arm of lever 13 is connected to the type bars (not shown) in a well known manner.

The lever 12 is actuated by the cam 11 when the latter engages the driven roller 10 to be

operated thereby. The engagement of the cam 11 with the power roller is controlled by means of the key lever 17 in a manner which will now be described.

The cam 11 is resiliently engaged by a spring-pressed arm 20 which tends to turn it into engagement with the power driven roller or stop 10 on a lever 22 pivoted on the bell crank 12 and normally arranged in the path of a lug on the cam. When the lever 22 swings to move its stop 10 out of the path of the lug, the arm 20 swings the cam into engagement with the power roller to be actuated thereby to swing the bell crank 12 to actuate its connected mechanism.

The lever 22 has an arm 24 which is provided with an offset projection 25 at its end which projects laterally through an opening in the bell crank 12 and engages the bifurcated lower end 26 of an arm 27 of a key lever 17 pivoted on the common rod 28.

It is obvious then that depression of a key lever 17 releases the revolvably mounted cam 11 to engage and be actuated by power roller 10 in turn operating bell crank 12 and its attached links to cause the associated mechanism, such as 25 the key bars and other operating mechanisms, to be operated.

The associated permutation bar mechanism will now be described and by referring to Figs. 1 and 2 is shown to comprise generally a plurality of round slotted shafts or bars 35, the slots 36 of which are arranged diametrically opposite one another. The said bars are normally maintained inoperative so that the control levers 37, one for each key bar and attached thereto, by link 37-a, are locked in an inoperative position. Gear units 41 (Fig. 4) are provided at each end of the permutation bar device, comprising three sets of gears, one for each shaft or bar 35. The gears 38, 39, and 40 are rotated continuously by drive gears 42 and are connected to the associated bars 35 by individual clutches 43 (Fig. 5) to drive said bars one revolution. The clutches 43 are controlled by magnets 44 which are energized by control signals and in combinations in accordance with the preferred permutation code. During the rotation of the selected bars 35 certain slots 36 disposed thereon are presented under the control levers 37 so that one control lever is selected and permitted to drop in the channel provided by the slots which are in alignment, operating the control lever and its attached key bar lever, thus causing the character to be recorded.

The permutation bars 35, of which six are shown, are supported in the end plates 45 (see

Fig. 3) attached to the gear units 41 which are secured to the supporting casting indicated generally at 46. To prevent sagging of the bars, central supporting posts 47 are provided. The 5 control levers 37 are positioned over the permutation bars 35 (Fig. 1), and are pivotally supported at the ends thereof by rod 48 suitably supported by members 49 attached to the supporting casting 46. Individual springs 50 are attached to the levers 37 to urge the levers against the permutation bars 35. The levers 37 at the other ends thereof are linked to the key bar connecting links 37-a, and therefore it will be seen that upon depression of a control lever 37 by spring 50 10 the link 37-a will be moved downwardly to lower the attached key bar and causing the associated type bar to be operated. The levers 37 are kept in correct alignment by means of the comb member 54 attached to the said supporting casting. 15

20 The entire supporting casting 46 is pivotally secured to members 51 so that the entire permutation bar unit may be rotated about the pivots 52 (Fig. 2) by removing nuts 53. The pivot line through the hinges 52 is in line with the center 25 of attachment of links 37-a and levers 37 so that the said unit may be hinged downwardly without disturbing the link connections to the key bars.

30 The permutation bars are slotted in accordance with any desired permutation code, the slotted bars are shown in detail in Figs. 7 to 7-E, the slots as shown are arranged so that upon rotation of certain of the bars, one control lever 37 is selected and permitted momentarily to be depressed into the slots by spring 50 thereby depressing the attached link 37-a and key bar 17. Referring to Fig. 1 it will be seen that the rotation of bars 35 Nos. 2, 4, and 6, will cause the slots of all the bars to be aligned under the particular control lever 37 shown, thereby permitting said lever to be lowered into the slots momentarily to depress the associated link and key bar, causing the corresponding type bar to be operated.

45 The bars are rotated as follows: the power driven roller 10 of the typewriter is adapted to rotate the shaft 55 by means of the connecting belt 56. Attached to said shaft is a pair of driving gears 42, the gears positioned so as to engage the gears 38 (Fig. 4) in each gear unit 41. The gears 38 are adapted to rotate the gears 39 and 40. Each of the gears 38, 39, and 40 is attached to individual stud shafts 56 (Fig. 5) upon which are mounted ratchet gears 57. Associated with each ratchet gear 57 is a clutch unit 43 which is secured to the permutation bar 35. A clutch unit 55 is provided for each bar. The principles of operation of the sets of clutch units and gear units are identical and consequently only one set need be explained. It will be seen from Fig. 4 that the 60 directions of motions of the clutch gears 38, 39, and 40 are different, and because of this fact the clutches 43 are made right-hand and left-hand to correspond thereto.

A controlling magnet 44 is provided for each clutch 43. Referring to Figs. 3 and 5, the magnet 44 is provided with an armature 60 secured to a clutch stop arm 61. The said arm, while the magnet 44 is deenergized, is adapted to engage the dog lift lever which maintains the dog 63 in the position shown in the figure to prevent engagement of the tooth 64 on the dog and the ratchet gear 57.

70 The clutch is shown to comprise (see Figs. 6 to 6B) a housing member 65 secured to the permutation bar 35. The member 65 is shaped so

as to receive the toothed dog 63. A spring post 66 is fixed in the said member 65 and acts as a guide for spring 66. The dog 63 is shaped so as to fit over the said spring and spring post and when mounted in the channel provided in the 5 housing member 65 it is seen that the spring 66 tends to urge or maintain the dog 63 to the right as viewed in Fig. 6-A. The dog 63 and housing member 65 are recessed so as to receive the dog lift lever 62 which when inserted in the 10 housing member is adapted to be rotated slightly or pivoted about one end thereof. The other end of the dog lift extends beyond the housing member and is arranged to engage the stop arm 61 whenever magnet 44 is deenergized. Movement 15 of the dog lift lever 62 moves the recessed dog 63 and when blocked by the stop arm 61 as shown in Fig. 5 positions the dog 63 to the extreme left hand position against the action of spring 66. A spring-pressed stop 67 engages a notch 68 provided in the housing member 65, the bar 35 to be rotated in a counterclockwise direction as viewed in the figure, thereby also locking the clutch unit 20 43 so long as the magnet 44 remains deenergized.

Upon energization of the magnet, its armature 60 is attracted and positioning the stop arm 25 downwardly about the pivot 69 and out of engagement and the path of dog lift lever 62. The spring 66 then forces the dog 63 to the right as viewed in Fig. 5 into engagement with the constantly rotating ratchet gear 57.

The signal condition impressed upon the magnet 44 lasts momentarily, so that the stop 61 is positioned in the path of the dog lift lever 62 before one revolution of the clutch has been completed. As the clutch is rotated by the gear 57 and completes its revolution the dog lift lever engages the stop 61, and as the clutch continues its rotation with the lift lever 62 held stationary by the stop 61, the said lift lever is rotated about 40 its end positioned in the housing member 65 to slide the toothed dog 63 out of engagement with the ratchet gear 57. When the tooth 64 is brought out of engagement with the said ratchet, driving power is removed from the clutch and permutation bar. The spring 66 within the dog 63 normally would have a tendency to rotate the permutation bar in a reverse direction and permit the tooth 64 to again engage the ratchet gear; however, as previously explained the clutch and bar 35 are locked in the inoperative position by means of the stop 67. Due to the relative high speed of operation, when the toothed dog is forced out of engagement with the ratchet by means of the stop 61, the momentum of the rotating permutation bar and clutch is sufficient to rotate the bar and clutch slightly beyond the position where the tooth 64 just becomes disengaged from the ratchet gear; this carry-over is sufficient to permit the spring-pressed stop 67 to engage the 55 notch 68 locking the clutch and bar against reversed rotation and insuring sufficient clearance between the dog tooth and the ratchet so as to prevent chattering.

The remaining permutation bars are rotated 60 in a like manner upon energization of the associated clutch magnets 44. The magnets are energized practically simultaneously so that when a particular combination of signals causes certain of the magnets to be energized, the corresponding permutation bars are permitted to be rotated one revolution, permitting one control lever 37 to drop in the aligned slots on the permutation bars, thereby recording a character on the power operated typewriter accordingly.

The design of the permutation bar unit should be such that the stroke of the lever 37 is about twice as great as necessary to operate the typewriter key bar. In this manner the clutches are permitted a wide margin of operation and provides sufficient tolerance to allow for variations in timing of the different magnets due to variations in time of arrival of the signals. With reference to Fig. 1, it is seen that when the permutation bars 2, 4, and 6 rotate one revolution, the first 90° thereof the levers 37 are all maintained in a locked position, the next 90° permits the selected lever to be pulled downwardly by spring 50, the next 90° locks up all the levers again and during the last 90° the bars are positioned as shown in the normal position. It is seen, therefore, that upon reception of a signal the bars are rotated, but even in this event all the control levers are maintained in a locked position except the selected one, in this manner making it impossible to depress more than one control lever and its associated key bar at a time.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. A device of the character described comprising, in combination, a keyboard comprising a plurality of operable key bars, a plurality of rotatable permutation members associated therewith, means to rotate predetermined combinations of said members and means to effect selection of certain of said key bars directly upon rotation of the said members.

2. A device of the character described comprising, in combination, a keyboard comprising a plurality of operable key bars, a plurality of rotatable permutation members associated therewith, means to rotate predetermined combinations of said members, and means included in said members to effect selection of certain of said key bars and means to effect the selection during the rotation of said members.

3. A device of the character described comprising, in combination, a keyboard comprising a plurality of operable key bars, a plurality of rotatable permutation members, and means to rotate certain combinations of said members simultaneously, including means to rotate the members one revolution, and means to effect selection of certain of said key bars upon rotation of the permutation members.

4. A device of the character described comprising, in combination, a plurality of operable control members, a plurality of rotatable permutation bars, electromagnetic means to control the rotation of combinations of said bars, and means to effect selection of certain control members including means to effect said selection during the rotation of said bars.

5. A device of the character described comprising, in combination, a plurality of operable control members, a plurality of rotatable permutation bars, electromagnetic means to control the rotation of combinations of said bars, means controlled by said electromagnetic means upon momentary operation thereof to limit the rotation of said bars one revolution, and means to effect selection of a control member including means to effect said selection during the rotation of the bars.

6. A device of the character described comprising, in combination, a keyboard comprising a plurality of operable key bars, individual control members associated with each key bar, a plurality of normally inoperative permutation members, means to operate certain of said permutation members, and means to select a predetermined control member determined by the positioning of the permutation members including means to effect the said selection immediately upon positioning of the permutation members thereby effecting operation of the associated key bar.

7. A device of the character described comprising, in combination, a keyboard comprising a plurality of operable key bars, individual control members associated with each key bar, a plurality of normally inoperative permutation members, means to rotate certain of said permutation members a predetermined timed interval, and means to select a certain control member including means to effect the said selection during the rotation of the permutation members thereby effecting operation of the associated key bar.

8. A device of the character described comprising, in combination, a keyboard comprising a plurality of operable key bars, individual control members associated with each key bar, a plurality of normally inoperative permutation bars, and means to rotate certain of said bars one revolution and means to select a certain control member during the rotation of the permutation bars thereby effecting operation of the associated key bar.

9. A device of the character described comprising, in combination, a keyboard comprising a plurality of operable key bars, individual control members associated with each key bar, a plurality of normally inoperative permutation bars, means comprising electromagnetic means to control the operation of certain of said bars, and means to select a certain control member determined by the positioning of the permutation bars including means to effect said selection during the positioning of the permutation bars thereby effecting operation of the associated key bar.

10. A device of the character described comprising, in combination, a keyboard comprising a plurality of operable key bars, individual control members associated with each key bar, a plurality of normally inoperative permutation bars, means adapted to rotate said bars, means comprising electromagnetic means, upon energization thereof, to render the rotating means effective to rotate certain of said bars and means to select a certain control member determined by the positioning of the permutation bars and during rotation thereof thereby effecting operation of the associated key bar, and means controlled upon deenergization of the electromagnetic means to render said rotating means inoperative.

11. A device of the character described comprising, in combination, a group of normally inoperative rotatable permutation members, a plurality of control members associated therewith, continuously rotating driving means, means to effect rotation of certain of the permutation members by the driving means for a pre-determined timed interval, and means to effect the selection of certain of the control members during the rotation of the permutation members.

12. A device of the character described comprising, in combination, a group of normally inoperative rotatable permutation members, a plurality of control members associated therewith, 5 continuously rotating driving means, individual means to connect each permutation member to the continuously rotating driving means for a pre-determined timed interval, and means to effect selection of certain of the control members during the rotation of the permutation members.
- 10 13. A device of the character described comprising in combination, a group of normally

inoperative rotatable permutation members, a plurality of control members associated therewith, continuously rotating driving means, signal control means to effect connection of certain of the permutation members to the said driving means, 5 thereby effecting rotation of the said permutation members, and means to effect selection of the control members during the rotation of the permutation members.
